US00D895190S

(12) **United States Design Patent** (10) Patent No.: **US D895,190 S**
Lee (45) Date of Patent: ** Sep. 1, 2020

(54) **LIGHTING FIXTURE**

(71) Applicant: **Lee Broom Limited**, London (GB)

(72) Inventor: **Broom Lee**, London (GB)

(**) Term: **15 Years**

(21) Appl. No.: **35/507,140**

(22) Filed: **Jan. 21, 2019**

(80) **Hague Agreement Data**

Int. Filing Date: **Jan. 21, 2019**

Int. Reg. No.: **DM/200464**

Int. Reg. Date: **Jan. 21, 2019**

Int. Reg. Pub. Date: **Aug. 2, 2019**

(51) **LOC (12) Cl. 26-05**

(52) **U.S. Cl.**

USPC **D26/86**

(58) **Field of Classification Search**

USPC D26/1, 2, 3, 24, 70, 72, 75, 78, 79, 80,
